CIGARETTE PACKAGE

Leo A. Schwartz, Oklahoma City, Okla.

Application September 7, 1938, Serial No. 228,829

8 Claims. (Cl. 206—48)

This invention relates to cigarette packages and the like; and more particularly, to one adapted to contain a package of matches.

There are a number of patents showing the broad idea of a combined match and cigarette package. However, they do not disclose a flexible cigarette package having a match chamber at the end formed by folding the material of the blank so that the edges or sides of the match chamber are of plural thicknesses, thereby being relatively stiff and shape retaining, the bottom of the match chamber being reinforced by a match sheet which is stapled to one of the surfaces and a striking surface secured to the closure lid of the match compartment, the whole being formed from a single blank.

The principal object of the invention is to provide a flexible cover for a cigarette, cigar, or tobacco package, so folded that a compartment is formed at one end to act as a closure for the package and form a compartment in which a book of matches may be placed, and at the same time, have a closure for the match compartment in which is formed a striking surface.

Other objects will be disclosed in the specification and drawing forming a part hereof as the detailed description thereof proceeds.

In the drawing:

Figure 1 is a perspective showing the match compartment closed;

Figure 2 is a perspective showing the lid open and the matches exposed;

Figure 3 is a vertical section taken on line 3—3 of Figure 1;

Figure 4 is a section taken on the line 4—4 of Figure 3; and

Figure 5 is a plan of the blank.

Referring to the drawing, in which similar parts are designated by like numerals:

Numeral 6 designates a package for cigarettes, cigars, tobacco and the like, of the usual construction, having a paper and tin foil wrap 8, with tucked ends 9. It is customary to have an outer wrap which carries the brand name and other data. In my application this is designated

10. As shown in Figure 5 it consists of a front 11 formed by score lines 12 and 13, sides 14 formed by score lines 15, and back 16, and the sealing flap 17. The top 18 has a score line 19. Extending from the top portion 18 is a tongue 22 with score line 20, which, when folded, forms a match receptacle and cover, a flap 21 fitting into the compartment.

As actually formed, the wrap 10 will be folded 55 on the various score lines 12, 13, 15 and 19, so

as to encircle the package, sealing flap 17 being to the rear, and the back 16 covering the sealing flap 17. The wrap 10 is made to extend above the top of the package so that upon the upper edge being folded inwardly along the score line 19, a reinforced edge or fold is provided. The tongue 22, upon being folded along the score line 20, forms the bottom 23 of the match chamber with the portion 24 forming a cover. A book of matches 25 is riveted or otherwise secured to the bottom 23, and abrasive material 26 is placed on the upper side of the cover 24. The portion 27 between the score lines 20 may be secured to the opposite side with adhesive. Likewise the turned-down portion above the score line 19 may be so secured. The book of matches 25 instead of being secured to the bottom 23, may be secured to the cover 24 so that upon the cover being opened, the matches will be available.

This construction presents a simple outside 20 cover formed from a single blank with matches and abrasive material which may be placed on the blank before folding, and which readily forms a unitary cover and match receptacle.

Numerous variations may doubtless be devised 25 by persons skilled in the art without departing from the principles of my invention. I, therefore, desire no limitations to be imposed on my invention, except such as are indicated in the appended claims.

What I claim is:

1. A wrapper for a cigarette package and the like comprising a main body adapted to enclose the front, sides and back of such a package, and having a downturned edge with a bottom closure 35 extending from front to back adjacent the downturned edge and below the level thereof, a match package secured to said bottom closure to reinforce the same, a cover closure forming a part of said bottom closure extending up the sides 40 and over the top, striking material on the cover closure, the downturned edges, bottom and cover closure forming a reinforced compartment of greater thickness than the rest of the wrap.

2. Wrapper for cigarette package comprising 45 a tubular sheet material envelope conforming to the shape of the cigarette package, having an infolded flat peripheral fold at one end and a transverse partition joining opposite edges of the base of said fold, a re-entrant chamber 50 being thus defined at one end of said wrapper of which said fold forms shape-retaining walls of double thickness, said partition constituting the bottom member of said chamber.

3. Wrapper for cigarette package comprising a 55

- tubular sheet material envelope conforming to the shape of the cigarette package, having an infolded flat peripheral fold at one end, the contacting plies of said fold being pasted together 5 and a transverse partition joining opposite edges of the base of said fold, a re-entrant chamber being thus defined of which said fold forms shape-retaining walls of double thickness, said partition constituting the bottom member of said re-entrant chamber.
- 10 4. Wrapper for cigarette package comprising a tubular sheet material envelope conforming to the shape of the cigarette package, having an infolded flat peripheral fold at one end, and a transverse partition joining the opposite edges of the base of said fold, a re-entrant chamber being thus defined of which said fold forms shape-retaining walls of double thickness, said partition constituting the bottom member of said re-entrant chamber, and a match comb within said chamber of substantially the same shape and size of said bottom member and secured thereto.
- 15 5. Wrapper for cigarette package comprising a tubular sheet material envelope conforming to the shape of the cigarette package having an infolded flat peripheral fold at one end and a transverse partition joining opposite edges of the base of said fold, a re-entrant chamber being thus defined of which said fold forms shape-retaining lateral walls of double thickness, said partition constituting the bottom member, a flap 20 extending from one of the top edges of said fold forming the top member of said chamber of substantially the same shape and size as said bottom member, a match comb of substantially the same shape and size as said members secured to one of them, said top member having a striking surface.
- 25 6. Wrapper for cigarette package comprising a tubular sheet material envelope conforming to the shape of the cigarette package having an infolded flat peripheral fold at one end, and a

transverse partition integral with the base edge of said fold on one side joining opposite edges of the base of said fold, a re-entrant chamber being thus defined of which said fold forms shape-retaining lateral walls of double thickness, 5 said partition constituting the bottom member of said chamber, said partition having an integral upwardly extending portion congruent with and pasted to one side of said fold, said portion having an integral extension forming the top member 10 of said chamber and being of substantially the same size and shape as said bottom member, and a match comb of substantially the same size and shape as said members secured to one of them, said top member having a striking surface. 15

7. Wrapper for cigarette package comprising a tubular sheet material envelope conforming to the shape of the cigarette package and open at one end, having an infolded flat peripheral fold at the opposite end, and a transverse partition joining opposite edges of the base of said fold, a re-entrant chamber being thus defined of which said fold forms shape-retaining walls of double thickness, said partition constituting the bottom member of said chamber. 20

8. Wrapper for cigarette package comprising a tubular sheet material envelope conforming to the shape of the cigarette package having a re-entrant chamber at one end formed with lateral walls of double thickness and having a transverse 30 partition joining opposite sides of said envelope at the base of said walls, forming the bottom member of said chamber, an extension from the top edge of said walls on one side forming a top member for said chamber, of substantially the same size and shape as said bottom member, and a match comb of substantially the same size and shape as said members, secured to one of them, said top member being provided with a striking surface. 35
